HOOD ORNAMENT FOR AN AUTOMOBILE

Milo J. O'Leary, Rochester, Mich., assignor to Chrysler Corporation, Highland Park, Mich., a corporation of Delaware

Application August 13, 1949, Serial No. 4,466

Term of patent 7 years

(Cl. D14—18)

To all whom it may concern:

Be it known that I, Milo J. O'Leary, a citizen of the United States, residing in the city of Rochester, county of Oakland, and State of Michigan, have invented a new, original, and ornamental Design for a Hood Ornament for an Automobile, of which the following is a specification, reference being had to the accompanying drawing, forming part thereof, in which:

Fig. 1 is a top plan view of my novel ornament;

Fig. 2 is a side elevation thereof; and

Figs. 3, 4, 5, 6, 7 and 8 are sections taken on a slightly enlarged scale on the lines 3—3, 4—4, 5—5, 6—6, 7—7 and 8—8, respectively, in Fig. 2.

The dominant features of my design are illustrated in full lines.

I claim:

The ornamental design for a hood ornament for an automobile, substantially as shown and described.

MILO J. O'LEARY.
